United States Patent Office

Des. 209,098
Patented Oct. 31, 1967

209,098

BOTTLE

Dieter Spiess, Talstrasse 11, Kleinkarlbach,
Pfalz, Germany

Filed July 11, 1966, Ser. No. 3,020

Term of patent 14 years

(Cl. D58—6)

FIG. 1

FIG. 2

I claim:

The ornamental design for a bottle, as shown and described.
